UNITED STATES PATENT OFFICE.

JAMES T. COWLEY, OF BOSTON, MASSACHUSETTS, ASSIGNOR TO LAMSON COMPANY, OF NEWARK, NEW JERSEY, A CORPORATION OF NEW JERSEY.

PNEUMATIC-DESPATCH-TUBE APPARATUS.

1,102,185.

Specification of Letters Patent. Patented June 30, 1914.

Application filed November 28, 1906. Serial No. 345,464.

To all whom it may concern:

Be it known that I, JAMES T. COWLEY, of Boston, in the county of Suffolk and State of Massachusetts, have invented certain new and useful Improvements in Pneumatic-Despatch-Tube Apparatus, of which the following is a specification.

My invention relates to improvements in pneumatic despatch tube apparatus and particularly to that class wherein a single tube is used for the transmission of carriers therethrough in either direction.

The object of this invention is to control the operation of the power for producing a current of air in either direction through the transmission tube as required and limiting and controlling the use of power to the interval necessary for the proper transmission and delivery of the carriers. This object is accomplished by utilizing a pneumatically-controlled switch which is adapted to be operated from either terminal of said tube to start or stop independently one of two oppositely-acting pressure-producing members or pumps.

In the accompanying drawings which illustrate a construction embodying my invention, Figure 1 is a diagrammatic view of a single-tube pneumatic system showing power connections therewith and mechanism for controlling the same. Figs. 2 and 3 are sectional views of the pneumatic pump-controlling mechanism hereinafter described. Fig. 4 is an elevation of the valve controlling mechanism regulating the direction of the air current. Fig. 5 is a detail view of the upper end of valve-controlling mechanism shown in Fig. 4. Fig. 6 is a plan view of one of the two pump controlling switches. Fig. 7 is a detail view of a portion of the switch shown in Fig. 6. Figs. 8 and 9 are enlarged detail views of the automatic timing device for stopping the pump. Fig. 10 is an enlarged view of the pressure-despatching and vacuum-receiving terminal of said transmission tube.

Like letters of reference refer to like parts throughout the several views.

Referring to Fig. 1.—A represents a central station and B a sub-station connected by the single transmission tube 1; the tube 1 is supported at station B by a standard 2 to

which is attached a receptacle 3 adapted to receive the carriers discharged at said station. At the central station A there is connected with the tube 1 a supply pipe 4 and supported by said pipe is a receptacle 5 adapted to receive carriers discharged from the tube at the central station A. At its lower end the supply pipe 4 is connected by a T with two pipes 6 and 7, the pipe 6 being connected with the exhaust port of a pump 8 and the pipe 7 being connected with the inlet port of a pump 9. Communication between the pipes 4, 6 and 7 is controlled by two valves 10 and 11. The inlet port of pump 8 is connected by a conduit 12 with a cylinder 13 which is part of the automatic timing mechanism for controlling the period of operation of the pump 8. The pump 8 is connected and driven by a belt with a motor 30.

The cylinder 13 is divided near its middle by a hollow partition 14 with which the conduit 12 communicates and in this partition there is an opening 15 connecting the conduit 12 with the lower part of the cylinder 13, and an opening 16 adapted to connect the conduit 12 with the upper part of the cylinder 13, which communicates with the atmosphere through port 17. Mounted in the lower part of cylinder 13 is a piston 18 whose connected rod 19 carries a valve 20 adapted to control the port 16 and a collar 21 fixed to its upper end and adapted to operate a switch 22 mounted on top said cylinder 13.

The conduit 12 is connected with the lower part of the cylinder 13 below the piston 18 by a by-pass 23 which is regulated by a screw-valve 24; located in this by-pass 23 is a port 25 normally closed to the atmosphere by a valve 26 mounted on an armature lever 27 pivoted at 28 in a bracket projecting from the cylinder 13. A spring 29 connected with said lever 27 normally holds the valve 26 closed. The motor 30 which drives the pump 8 has one terminal connected by a wire 31, switch 32 and wire 33, with a line wire L'. The other terminal of said motor is connected by a wire 34 with one of a pair of contacts 35, the other of said contacts being connected by a wire 36, switch 32 and wire 37 with the opposite line wire L². The

contacts 35 are normally disconnected, but a bridge piece 38 on the armature of a magnet 39 is provided to connect said contacts and start motor 30 when the magnet 39 is energized.

The pump 9 is driven by a motor 40, one terminal of which is connected by a wire 41, switch 42 and a wire 43 with the line wire L', while the other terminal of said motor 10 40 is connected by a wire 44 with one of a pair of contacts 45, the other of said contacts being connected by a wire 46, switch 42 and wire 47 with the opposite line wire L². The contacts 45 are normally disconnected but are adapted to be connected to start motor 40 by a bridge-piece 48 carried by the armature of a magnet 49 when said magnet is energized.

The valves 10 and 11 as shown most clearly in Fig. 4, are operated by a member 50 pivoted at 51 to the pipe 4. The lower end of member 50 when swung in one direction is adapted to engage an arm 52 fixed to the stem of valve 11 and open said valve, and when swung in the opposite direction, is adapted to engage an arm 53 and open valve 10, and as will be clear, when one valve is opened, the other valve is left in its normal or closed position. The arms 52 and 53 25 carry weights 54 which return the valves to and hold them in their normal closed positions with the arms 52 and 53 against stops 55. Other stops 56 are also provided to engage the weight 54 and limit the opening 30 movement of each valve to about one-quarter of a revolution. The member 50 is swung to the right in Fig. 4 to open valve 11 by means of a magnet 57, and to the left in said figure to open valve 10 by a hand-operated 35 lever 58 pivoted at 59 which acts through a stem 60 and links 61 to swing the member 50 in that direction. This movement of member 50 to the left is actuated by a swinging movement of lever 58 to the right in Fig. 4 at which time said lever engages a laterally projecting pin 62 on the stem 60, which pin is so placed with relation to lever 58 that when the latter is held in its normal position by a returning spring 63, there is 40 lost motion provided for between pin 62 and lever 58 sufficient to allow the magnet 57 to swing member 50 to the right independently of the lever 58. The lever 58 is located at station A and is controlled by the operator to open valve 10 while the closing of said valve 10 is controlled through the return movement of member 50 by the pressure in the pipe 4. To provide for this, the stem 60 extends 45 through a chamber 64, the latter being connected at one side of the diaphragm 65 with pipe 4 by a conduit 66. The magnet 57 is controlled by the operator at station B and to provide for this, the circuit 67 of magnet 57 contains a switch 68 whose movable arm

69 is connected with and operated by a movement of the stem 70 which extends through a chamber 71 and has fixed to it a diaphragm 72 mounted centrally in said chamber. At one side of diaphragm 72 is a 70 spring 73 which normally holds the stem 70 at one extreme of its movement with switch member 69 open. The chamber in the casting 71 on the opposite side of the diaphragm 72 is connected by a conduit 74 with another diaphragm chamber 75 within which is a diaphragm 76 mounted at its middle with a stem 77 which in turn is connected with a hand lever 78 through which said diaphragm 75 may be operated as a pump to transmit an 75 impulse of air through the conduit 74 to chamber 71, and through means of diaphragm 72 and stem 70, to close switch 68. In this way, the operator at station B closes the circuit 67 of magnet 57 which results in 80 the member 50 being swung to the right (Fig. 4) to open the valve 11.

When the operator at station A operates the lever 58 to open the valve 10, the pump 8 is automatically started and a current of air is established from said pump in the direction indicated by the arrow through pipe 6 and supply pipe 4 and through the transmission tube 1 in the direction indicated by full line arrow; and when magnet 57 is energized by the operator manipulating the lever 78 at sub-station B to open the valve 11, the pump 9 is started creating a current of air through the tube 7 supply pipe 4 and transmission tube 1 in the opposite direction as indicated by the dotted line arrow (Fig. 1).

In order to provide for automatically starting one or the other of the two pumps according to which of the two valves is 105 open, the circuits of the magnets 39 and 49 are automatically operated and controlled by the member 50 as follows: To the upper end of member 50 is fixed a block 79 of insulating material (Fig. 4) on which is 110 mounted four spring contact arms 80 arranged in two pairs connected by the metal strap or bond 81, so that electrically all the arms 80 are as one (Figs. 4-5). Just above the arms 80 are two pairs of contacts 82 and 83 so arranged that when member 50 is 115 swung to the left to open valve 10, the arms 80 connect the contacts 82, and when swung to the right to open the valve 11, the arms 80 connect the contacts 83. The contacts 82 and 83 are fixed to and insulated from the metal blocks 84 mounted on an insulated arm 85 projecting from the pipe 4. The contacts 82 are electrically connected as shown in Fig. 5 with binding posts 86 by 120 wires 87, while the contacts 83 are connected by wires 88 with binding posts 89; one of the binding posts 86 is connected by a wire 90 with one end of the coil of magnet 39. The other end of the coil of said mag- 125

net is connected by a wire 91 with one of the two contacts 92 of switch 22, while the other contact 92 is connected by wire 93 through a battery and to the other binding post 86. The other binding posts 89 are connected by wires 94 and 95 with a battery and the ends of the coil of the magnet 49. It will thus be clear that the member 50 when swung in one direction by means of lever 58 to open valve 10 will close the contacts 82 by means of arms 80, thereby energizing the magnet 39 and that also, when the member 50 is swung in the opposite direction by operating the lever 78 to open the valve 11, the arms 80 bridge contacts 83 thereby energizing the magnet 49.

It is obvious that when the magnet 39 is energized, it attracts its armature and the circuit of motor 30 is closed at 35 and said motor is started operating the pump 8; simultaneously with the starting of pump 8, the valve 26 is opened and the atmosphere is admitted beneath the piston 18 causing said piston to be quickly raised to its highest point, thus opening the valve 20 so that air is then supplied to pump 8 through the ports 17 and 16 and conduit 12. The current of air thus established in the transmission tube 1, drives the carrier from the central station A to the sub station B. The valve 26 is only momentarily opened, and as soon as the piston 18 reaches its highest point, the valve 26 is closed again, and the piston gradually descends by gravity to the lower part of the cylinder 13 by means of the exhausting of the air from under said piston, through by-pass 23 and conduit 12. As the piston 18 reaches its lowest position, the collar 21 engages a latch 96 pivotally mounted on a movable member 97 of the switch 22, and opens said switch, thereby breaking the circuit of magnet 39 whose armature falls away from contacts 35, thus breaking the circuit of motor 30, and stopping the pump 8. The descent of the piston 18 is regulated by the adjustable valve 24 permitting a sufficient interval of time to elapse before operating the switch 22 and stopping the motor 30 for the proper transmission and delivery of the carrier at the sub station B. The purpose of the pivoted latch 96 is to prevent the collar 21 from operating the switch 22 during the ascent of said collar and to momentarily operate to open said switch in its descent, the said switch closing automatically by gravity after the collar 21 passes below the latch 96. To operate the valve 26 as described, a magnet 98 is provided co-operating with the armature 27, on lever 27 and the circuit 99 of this magnet includes two normally disconnected contacts 100 which are bridged by the lever 58 when said lever is swung to the right as described. It is intended that after the lever 58 has been swung by the op-

erator to the right to the extreme of its movement, it shall be immediately released and returned automatically by the spring 63 to its normal position breaking the circuit 99, de-energizing the magnet 98 and closing the valve 26 by means of the spring 29.

In sending a carrier from sub-station B to central station A, the operator at station B swings the lever 78 to the left and the impulse of air through the pipe 74 shifts the diaphragm 72 and stem 70 to the right, thus closing the switch 68, and energizing magnet 57. The member 50 is now swung to the right opening valve 11 and closing the circuit of magnet 49 through arms 80 bridging contacts 83. The resulting movement of the armature of magnet 49 closes the circuit of motor 40 at 45 and said motor and pump 9 are started into action.

While the carrier is in transit from station B to station A, the pressure between the carrier and the pump 9 is below atmospheric and therefore the diaphragm 65 will be held in the position indicated by dotted lines at *w* (Fig. 4) owing to the ports 101 provided in the chamber 64 admitting the atmosphere to that side of the diaphragm, the opposite side of said diaphragm being in communication with the supply pipe 4 through pipe 66. As soon as the carrier discharges from the transmission tube at station A, the pressure in the pipes 7 and 4 and in the transmission tube 1 returns practically to atmospheric, and the resiliency of the diaphragm 65 acting through stem 60 and link 61, returns the member 50 to its normal intermediate position. As has been heretofore described, the lever 58 is free of the stem 60 except for the pin 62, the lost motion between pin 62 and lever 58 permitting the stem 60 to move independently of the lever 58 to the left (Fig. 4) and to remain there with the diaphragm 65 in dotted line position indicated at *w* while the pump 9 is in action. This connection between lever 58 and stem 60 also permits the lever 58 to be returned by spring 63 independently of stem 60, while pump 8 is in action, and diaphragm 65 is held in the dotted line position indicated at *y* (Fig. 4) by the air forced through pipe 66 into chamber 64.

As the pressure required in the transmission tube 1 to despatch a carrier from the central station A to the sub station B is greater than atmospheric pressure, it is necessary to hold the valve controlling the end of the tube at station A securely closed. When a carrier is being despatched from sub-station B to central station A, the pressure in the tube 1 being less than atmosphere holds the valve closed. To serve this double object, I provide a latch 107 pivoted at 108 to the transmission tube 1 at central station A. The tail of the latch 107 co-
-130

erates with a cam 109 pivoted at 110, and which cam is adapted to be operated by a trip 111 one end of which extends through a slot in the transmission tube 1 into the path of traveling carriers.

When a carrier is being despatched from sub station B to central station A, it strikes the trip 111, causing the cam 109 to swing the latch 107 out of engagement with the arm 104 pivoted at 105 and to which is attached a valve 103, allowing said valve to be opened upon the impact of the carrier thereon. After the discharge of the carrier, the arm 104 and valve 103 are returned to normal position by a spring 106. It is necessary that the distance between the trip 111 and the valve 103 should be less than the length of the carrier, as this trip must be held depressed and the latch 107 released from the arm 104 at the time the forward end of the carrier strikes the valve 103.

In despatching a carrier from the central station A to the sub-station B, the lower end of the latch 107 is pressed outward releasing the arm 104 and opening the valve 103 when the carrier may be inserted into the transmission tube 1. As the trip 111 does not operate upon the latch 107 when the carrier is inserted into the tube for transmission from A to B, the latch is permitted to engage the arm 104 after the carrier has been inserted, which latch 107 holds the valve 103, securely closed against the high pressure necessary to drive the carrier in this direction to its destination.

Having thus described the nature of my invention and set forth a construction embodying the same, what I claim as new and desire to secure by Letters Patent of the United States is:

1. In pneumatic despatch tube apparatus, a transit tube for the transmission of carriers in either direction, pressure and exhaust pumps communicating with the same end of the transit tube, independent valves normally closed controlling the communications between the pumps and the transit tube, valve-operating mechanism common to both valves operating to open one or the other valve to establish communication between the transit tube and either pump, a motor for each pump, and means actuated by the valve-operating mechanism to set in motion the motor for the pump between which and the transit tube communication is established by said valve-operating mechanism.

2. In pneumatic despatch tube apparatus, a transit tube for the transmission of carriers in either direction, pressure and exhaust pumps communicating with the near end of the transit tube, independent valves normally closed controlling the communications between the pumps and the transit tube, valve-operating mechanism common

to both valves operating to open one or the other valve to establish communication between the transit tube and either pump, a motor for each pump, means actuated by said valve-operating mechanism to set in motion the motor for the pump between which and the transit tube communication is established by said valve-operating mechanism, means controlled at the near end of the transit tube for actuating said valve-operating mechanism to open the valve controlling the communication between the transit tube and the pressure pump, and means controlled at the far end of the transit tube for actuating said valve-operating mechanism to open the valve controlling the communication between the transit tube and the exhaust pump.

3. In a pneumatic despatch tube system, a transit tube for the transmission of carriers, said tube having a plurality of terminals, one at least of which is normally open and adapted for the reception of carriers, air displacing means for exhausting air from said tube for transmitting said carriers, an air exhaust conduit between said air displacing means and the transit tube, a valve, adapted to throttle communication between said pump and transit tube, valve actuating means having a tendency to move into a determined position, said actuating means adapted to move said valve to a corresponding position when permitted to respond to said tendency and adapted to be held out of said determined position only so long as at least a determined partial vacuum is maintained in a part of said conduit to one side of said valve, said valve being held open through the instrumentality of said actuating means normally substantially only so long as a carrier is in transit and the emergence of the carrier at its delivery terminal permitting the entrance of air at substantially atmospheric pressure to the said part of said conduit to substantially destroy the partial vacuum therein and effect the closure of said valve.

4. In pneumatic despatch tube apparatus, a transit tube for the transmission of carriers, an exhaust pump communicating with the near end of the transit tube, a normally closed valve controlling the communication between the pump and the transit tube, an electric motor to drive said pump having a normally open switch in its circuit, an electro-magnet with a normally open circuit for closing the switch of the electric motor when said electro-magnet is energized, a pivoted lever operating to open said valve and to close the circuit through the electro-magnet, a second electro-magnet when energized for moving said lever to open the valve and to close the circuit of the first electro-magnet, a normally open switch in the circuit of the second electro-magnet, a pneumatic motor

for operating the switch to close the circuit through the second electro-magnet, and a pneumatic pump at the far end of the transit tube communicating with said pneumatic motor to operate the latter to close the switch in the circuit of the second electro-magnet to energize the latter.

5. In a pneumatic despatch tube apparatus, a transit tube for the transmission of carriers, a pump in communication with said transit tube, a valve having a bias for its closed position, said valve controlling the communication between said pump and tube, mechanism for opening said valve, a valve controlling pneumatic device in communication with said transit tube and pump, said device including a wall adapted to be moved from a determined and normal position thereof to a second position, by the establishment of a difference in pressure in said tube created by said pump, said wall adapted to maintain said valve open when in its said second position and having a tendency to resume its normal position to effect the reclosure of said valve upon the dis-establishment of said difference in pressure.

6. In a pneumatic despatch tube system, a transit tube for the transmission of carriers, said tube provided with terminals, one at least of which is provided with a normally closed valve, means for establishing a carrier propelling current of air in said tube, said means having provisions tending to dis-establish said air current, a pneumatic device in communication with a part of the system and having a portion thereof responsive to changes in pressure in said part, said portion of said pneumatic device having a tendency for a determined position but adapted to be held out of said position by a given pressure of air in said part of the system, said device adapted to prevent the dis-establishment of said air current by the provisions aforesaid so long as said given pressure continues.

7. In a pneumatic despatch tube system, a transit tube for the transmission of carriers, means for establishing a carrier propelling current of air in said tube, said means having provisions tending to dis-establish said air current, a pneumatic device in communication with a part of the system and having a portion thereof responsive to changes in pressure in said part, said portion of said pneumatic device having a tendency for a determined position but adapted to be held out of said position by a given pressure of air in said part of the system, said device adapted to prevent the dis-establishment of said air current by the provisions aforesaid so long as said given pressure continues and means including a timing mechanism, for effecting an operative departure from said

given pressure in said part of the system whereby to permit said portion to move into its said determined position.

8. In a pneumatic despatch tube system, a transit tube for the transmission of carriers, said tube provided with terminals, one at least of which is a despatching terminal, means for establishing a carrier propelling current of air in said tube, said means having provisions tending to dis-establish said air current, a pneumatic device in communication with a part of the system and having a portion thereof responsive to changes in pressure in said part, said portion of said pneumatic device having a tendency for a determined position but adapted to be held out of said position by a given pressure of air in said part of the system, said device adapted to prevent the dis-establishment of said air current by the provisions aforesaid so long as said given pressure continues, and means including a timing mechanism for effecting an operative departure from said given pressure, in said part of the system, whereby to permit said portion to move into its said determined position, said timing mechanism adapted to be re-timed for each successive carrier transmitted from said despatching terminal.

9. In pneumatic despatch tube apparatus, a transit tube for the transmission of carriers, means for supplying compressed air to said tube or for exhausting air therefrom in accordance with the direction of travel of a carrier therethrough, said means including two conduits, one for delivering compressed air to said tube and one for conveying away air exhausted therefrom, together with mechanism for switching one or the other of said conduits into communication with said tube, and means for maintaining operative said mechanism after being set for switching air through the conduit selected, said last mentioned means comprising a pneumatic device in communication with said tube and having a wall thereof displaceable from a position which it normally occupies by the establishment of a difference in pressure in said tube, said wall having operative connections with a part of said switching mechanism adapted to hold said part substantially in the position into which it was moved when said mechanism was set.

10. In a pneumatic despatch tube system, tubular means for guiding carriers in transit between two stations, means for transmitting carriers from one of said stations to another by air above atmospheric pressure and for transmitting carriers from said other station to that first mentioned by air at substantially atmospheric pressure, timing mechanism for limiting the flow of air transmitting carriers one way, and means, operable by a change in pressure of

the air in a part at least of said tubular means, caused by the passage of a carrier past a determined point in said means, for limiting the flow of air transmitting carriers in an opposite direction.

11. In a pneumatic despatch tube system, tubular means for guiding carriers in transit between two stations, means for transmitting carriers from one of said stations to another by air above atmospheric pressure and for transmitting carriers from said other station to that first mentioned by air at substantially atmospheric pressure, timing mechanism for limiting the flow of air transmitting carriers one way, and means, operable by a change in pressure of the air in a part at least of said tubular means, caused by the passage of a carrier past a determined point in said means, for limiting the flow of air transmitting carriers in an opposite direction, a part of said last mentioned means acting to maintain the flow of air transmitting carriers in the first mentioned direction.
12. In a pneumatic despatch tube system, tubular means for guiding carriers in transit between two stations, means for transmitting carriers from one of said stations to another by air above atmospheric pressure and for transmitting carriers from said other station to that first mentioned by air at substantially atmospheric pressure, a part of said means having a tendency for a position in which it is adapted to render said means inoperative, and a pneumatic device in communication with said tubular means for holding said part out of said position during the continuance of carrier transmitting conditions in either direction in said system.
13. In a pneumatic despatch tube system, tubular means for guiding carriers in transit between two stations, means for transmitting carriers from one of said stations to another by air above atmospheric pressure and for transmitting carriers from said other station to that first mentioned by air at substantially atmospheric pressure, a part of said means having a tendency for a position in which it is adapted to render said means inoperative, a pneumatic device in communication with said tubular means for holding said part out of said position during the continuance of carrier transmitting conditions in either direction in said system, and means, including a timing mechanism, for automatically dis-establishing said conditions, whereby to effect the release of said part.

14. In a pneumatic despatch tube system, tubular means for guiding carriers in transit between two stations, means for transmitting carriers from one of said stations to another by air above atmospheric pressure and for transmitting carriers from said other station to that first mentioned by air at sub-

stantially atmospheric pressure, a part of said means having a tendency for a position in which it is adapted to render said means inoperative, and a pneumatic device in communication with said tubular means for holding said part out of said position during the continuance of carrier transmitting conditions in either direction in said system, said system having provisions for effecting the release of said part after the transmission of a carrier.

15. In a pneumatic despatch tube system, tubular means for guiding carriers in transit between two stations, means for transmitting carriers from one of said stations to another by air above atmospheric pressure and for transmitting carriers from said other station to that first mentioned by air at substantially atmospheric pressure, a part of said means having a tendency for a position in which it is adapted to render said means inoperative, and a pneumatic device in communication with said tubular means for holding said part out of said position during the continuance of carrier transmitting conditions in either direction in said system, said system having provisions, including a timing mechanism, for effecting the release of said part after the transmission of a carrier.

16. In a pneumatic despatch tube system, a transit tube for the transmission of carriers, said tube provided with terminals one at least of which has a closure, means co-acting with said closure for establishing a carrier propelling current of air in said tube, said means having a part thereof normally tending to dis-establish said air current, a pneumatic device in communication with said tube and having a portion thereof responsive to changes in pressure in the air therein and adapted to be held in one determined position by a given pressure of air in said tube, said device adapted to restrain the part aforesaid against movement by its said tendency so long as said given pressure continues.

17. In a pneumatic despatch tube system, a single tube adapted for the transmission of carriers in either direction therethrough, a normally non-reversible pump adapted to be placed in communication with said tube for transmitting carriers one way by compressed air, a second normally non-reversible pump adapted to be placed in communication with said tube for transmitting carriers therethrough in the opposite direction, means for placing one or the other of said pumps in communication with said tubes in accordance with the requirements of service conditions in the system, and means for starting one or the other of said pumps in accordance with the communications established by said last mentioned means, said system having provisions for stopping the

pump which is in operation and dis-establishing communication therewith after the transmission of the carrier through said tube.

- 5 18. In a pneumatic despatch tube system, having a plurality of stations, means relatively remote from one of said stations for establishing a carrier propelling current of air flowing from said station toward 10 another of said stations said last mentioned means including an electric circuit having therein a switch, a source of electric current in circuit with said switch and an electro-magnetic device, means controlled by 15 said device for creating a difference in pressure in the air in said tube at the respective stations aforesaid, and pneumatic means for rendering operative said first mentioned means, said pneumatic means including an 20 auxiliary tube for transmitting air under pressure from said first mentioned station substantially to said switch, a pneumatic device in communication with said last mentioned tube for actuating said switch and 25 means at said first mentioned station for creating a difference in pressure in said auxiliary tube.

19. In a pneumatic despatch tube system, a transit tube for the transmission of carriers, said tube having a plurality of terminals, one at least of which is normally open and adapted for the reception of carriers, air displacing means for exhausting air from said tube for transmitting said 30 carriers, an air exhaust conduit between said air displacing means and the transit tube, a valve, adapted to throttle communication between said pump and transit tube, valve actuating means having a tendency to move 35 into a determined position, said actuating means adapted to move said valve to a corresponding position when permitted to respond to said tendency and adapted to be held out of said determined position only 40 so long as at least a determined partial vacuum is maintained in a part of said conduit to that side of said valve which is the more remote from said pump, said valve being held open through the instrumentality 45 of said actuating means normally substantially only so long as a carrier is in transit and the emergence of the carrier at its delivery terminal permitting the entrance of air at substantially atmospheric pressure to 50 the said part of said conduit to substantially destroy the partial vacuum therein.

20. In a pneumatic despatch tube system, a transit tube for the transmission of carriers, said tube having a plurality of terminals, one at least of which is normally open and adapted for the reception of carriers, air displacing means for exhausting air from said tube for transmitting said carriers, an air exhaust conduit between said 60 air displacing means and the transit tube,

a valve, adapted to throttle communication between said pump and transit tube, resilient valve actuating means having a tendency to move into a determined position, said means adapted to move said valve to 70 a corresponding position when permitted to respond to said tendency and adapted to be held out of said determined position only so long as at least a determined partial vacuum is maintained in a determined part of 75 said conduit, said valve being held open through the instrumentality of said means normally substantially only so long as a carrier is in transit and the emergence of the carrier at its delivery terminal permitting 80 the entrance of sufficient air through said open terminal to said determined part of said conduit to destroy said partial vacuum therein.

21. In a pneumatic despatch tube system, 85 a transit tube normally open to the atmosphere, a carrier, air displacing means for creating a carrier transmitting current of air through said tube, a valve between said tube and said air displacing means adapted to 90 control said current of air, said system having parts disposed in adjacency to said valve and adapted to co-act therewith to permit a free flow of said air current only so long as there exists a determined relationship 95 between the pressure in said transit tube and that in the side of said air displacing means which is connected to said tube, the emergence of the carrier from the tube destroying 100 said determined relationship.

22. In a pneumatic despatch tube system, a transit tube normally open to the atmosphere, a carrier, air displacing means for creating a carrier transmitting current of air through said tube, an element between 105 said tube and said air displacing means adapted to directly control said current of air, said system also having auxiliary elements disposed in adjacency to said first mentioned element and adapted to co-act 110 therewith to permit a free flow of said air current only so long as there exists a determined relationship between the pressure in said transit tube and that in the side of said air displacing means which is connected 115 to said tube, the emergence of the carrier from the tube destroying said determined relationship, one of said elements being resilient and tending thereby to move into a determined position, said resilient one of 120 said elements being adapted to be held out of said position by air pressure and to move to its said determined position when pressure upon opposite sides thereof is substantially equalized.

23. In a pneumatic despatch tube system, a transit tube normally open to the atmosphere, a carrier adapted for transmission through said tube, means connected with said tube for creating a carrier propelling 125 130

current of air therethrough, a valve for controlling communication between said tube and said means, said system having parts to co-act with said valve to permit a free flow 5 of said air current only so long as there exists a determined relationship between the pressure in the transit tube and that in the side of said means which is in communication with the tube, the emergence of said 10 carrier from the tube substantially destroying said determined relationship.

24. In a pneumatic despatch tube system, a transit tube normally open to the atmosphere, a carrier adapted for transmission 15 through said tube, a pump for exhausting air from said tube to propel said carrier therethrough, said tube having a terminal through which said carrier may be inserted, and said system, further, having means, controlled by the current of air which enters 20 the normally open tube behind said carrier, to normally throttle communication between said tube and pump when said carrier has

passed a determined point in said tube to permit access of said air to said means. 25

25. In a pneumatic despatch tube system, a transit tube normally open to the atmosphere, a carrier adapted for transmission through said tube, means for creating a carrier transmitting flow of air through said 30 tube, said tube having a terminal through which said carrier may be inserted, and said system, further, having fluid pressure controlled means operative upon the passage of the carrier past a determined point in said 35 tube, to throttle communication between said tube and said first mentioned means.

In testimony whereof, I have signed my name to this specification in the presence of two subscribing witnesses, this twenty-second day of November A. D. 1906.

JAMES T. COWLEY.

Witnesses:

C. ROBERT LIBBY,
W.M. H. KNOWLTON.
